UNITED STATES PATENT OFFICE.

JOHN WILLIAM WADSWORTH, OF DRAYTON, ENGLAND, ASSIGNOR TO MINTONS
LIMITED, OF STOKE-UPON-TRENT, ENGLAND.

DESIGN FOR A PLATE OR SIMILAR ARTICLE.

41,656.

Specification for Design.

Patented Aug. 8, 1911.

Application filed May 11, 1911. Serial No. 626,591. Term of patent 7 years.

To all whom it may concern:

Be it known that I, JOHN WILLIAM WADSWORTH, a subject of the King of Great Britain and Ireland, residing at Drayton, Staffordshire, England, have invented a new, original, and ornamental Design for a Plate or Similar Article, of which the following is a specification.

In the accompanying drawing, the figure is a plan showing the design.

I claim:

The ornamental design for a plate or similar article as shown.

In testimony whereof I have affixed my signature in presence of two witnesses.

JOHN WILLIAM WADSWORTH.

Witnesses:

WILLIAM DUDLEY,
PATTIE PLANT.
